YARN CLEARER

Louis Régley, Troyes, France

Application April 8, 1932, Serial No. 604,059
In France May 1, 1931

3 Claims. (Cl. 28—68)

Textile industry necessitates the use of yarns free from defects (thick places or beads, staples, pads, kinks, double threads, differences of twists) prejudicious to the proper operation of the machines utilizing them, and to the appearance of the fabrics obtained.

It is therefore necessary to clear these yarns, either upon spinning, or upon spooling.

Use is made for that purpose of apparatus called clearers; these apparatus are usually provided with slots through which the yarn passes, and are constituted for that purpose: either by two parallel blades arranged in one and the same plane and the spacing apart of which is adjusted as desired, or by a disc having radial slots of different widths, or, finally, by two blades arranged in one and the same plane and forming together a V-shaped slot.

These apparatus have this inconvenience that 20 they clear the yarn only in one plane, thus producing a kind of rolling which ensures but an imperfect clearing.

It has been attempted to clear yarns in two 25 different planes, by compelling them to successively pass between two sets of blades having two slots at right-angles to each other and giving, in projection on a plane parallel to the blades, an orifice of trapezoidal shape closely approximating a square shape.

30 But the distance which must be left between the two sets of blades for allowing the insertion of the yarn is usually such that it allows the yarn to turn over while it is passing between the two slots; so that it is subjected only to two successive rollings and that clearing is still far from perfect.

The present invention has for its object a device so arranged as to avoid these inconveniences and to ensure a complete clearing of the yarn, 40 by passage, not through a slot, or through two slots spaced apart, but through an orifice of adjustable cross-section constituting a die or draw-plate capable of controlling the diameter of the yarn to be cleared.

45 The device according to the invention comprises two small plates, each provided with a notch and fitted against each other, so that both notches are located opposite each other and form an orifice in which the yarn is engaged.

50 During normal operation, these small plates are locked against each other in the desired position, so that the device is the equivalent of a die or draw-plate arranged in the plane of contact of both plates, and stops any defect giving to the

yarn a diameter greater than that of the orifice of the die or draw-plate.

The cross-section of this orifice can be adjusted by causing both plates to slide relatively to each other so as to more or less space apart the edges of their notches.

For causing the relative sliding movement of both plates, a control is in particular provided by means of inclined slides allowing to effect the adjustment with very great accuracy.

10 The accompanying drawings illustrate, by way of example only, two forms of carrying out the subject-matter of the invention, in which it will be assumed that the shape chosen for the orifice is a square and to modifications the orifice of 15 which has the shape of a lozenge and of a triangle respectively.

In the drawings:
Figs. 1 to 6 illustrate a first form of construction:

Fig. 1 shows the support of the apparatus.

Fig. 2 illustrates the member forming two sides of the square.

Fig. 3 shows the entire member constituting the two other sides.

Fig. 4 is a side view of Fig. 3.

Fig. 5 shows the two preceding members assembled together.

Fig. 6 is a perspective view of the entire device.

Figs. 7 to 10 illustrate a second form of construction.

Fig. 7 is a front view of the fixed support.

Fig. 8 is a similar view of this support and of the adjusting bar assembled together.

Fig. 9 is a similar view of the entire apparatus, 35 without the locking device.

Fig. 10 is a section made according to line X—X of Fig. 9, the locking device being assumed to be in position.

Fig. 11 shows a form of construction in which the hole for the passage of the yarn is in the shape of a lozenge.

Fig. 12 shows a form of construction in which the hole for the passage of the yarn has the shape of a triangle.

In the first form of construction, Fig. 1 shows a support 1 having two slots: one, 2, vertical, the other, 3, slightly oblique.

A small plate 4 (Fig. 2) has a right-angled notch 8, forming two of the sides of the square, 50 and carries two pins or studs 5, 6 adapted to be fitted in the slot 3 and to slide in the latter; in this plate 4 is also provided a slot 7 parallel to the diagonal of the square.

Fig. 4 shows a small plate 11 carrying, on one

of its faces, a resilient blade 9, and, on the other face, two pins or studs 12, 13.

In position of assembly, the pin 12 passes through the slot 7 and extends into the slot 2, and 5 the pin 13 fits into this slot 2.

The blade 9 is provided with a right-angled notch 10, adapted to cooperate with the notch 8 in order to constitute the two other sides of the square.

10 The pin 12 is provided with a screw-threaded part adapted to receive a locking nut 14.

The operation is as follows:

The small plate 4 is fitted against the plate 11, so that the pin 12 enters the slot 7 (Fig. 5). The 15 blade 9 is bent so as to compensate for the thickness of the plate 11 and to exactly fit against the plate 4. The entire structure is fitted behind the support 1, so that the pins 5 and 6 enter the slot 3, and the pins 12 and 13 enter the slot 2.

20 If a vertical movement, for instance an upward movement, is imparted to the pin 12, this causes the upward sliding movement of the two members 4 and 11—9.

The inclination of the slot 3 compels the plate 25 4 to slide towards the left of the drawings, and, owing to the inclination of the slot 7 parallel to the diagonal of the square, this sliding movement causes a displacement of the notch 8 relatively to the notch 10 parallel to one of the diagonals 30 of the square, so that both notches form a square of increasing dimensions.

Reversely, when the pin 12 is moved downwardly, the dimensions of the square decrease.

When the cross-section of the square is adjusted, the nut 14 allows of clamping the various 35 members against each other and to lock the device.

This nut can be so arranged that it can be operated only by means of a special wrench preventing any fraudulent use.

In order to facilitate the adjustment, a scale, for instance, can be traced on one of the sides of the member 1, and an index moving over this scale can be secured to one of the pins 12 or 13.

45 For passing the yarn, it suffices to move the spring or blade 9 away from the member 4 by a slight backward pressure, to then cause the yarn to enter the interval formed between the two members thus spaced apart, to bring it to the bottom of the angle 10, and to let the spring or blade come back again against the member 4.

The relative displacements of the notches 8, 10 can be rendered more or less rapid by more or less inclining the slot 3 relatively to the vertical. 55 It is to be noted that by giving to this slot a relatively small inclination, the displacement can be rendered very slow, and, consequently, a very accurate adjustment can be effected.

In the second form of construction, the notch 60 10 is provided in the support 15 of the apparatus. This support is provided with side lugs 15^a in which are formed holes 15^b for securing the said support in position. Its front face carries an oblique projecting guide 16 and, in alignment with 65 the axis of this guide, it also carries a pin 17.

With the said guide cooperates an adjusting bar 18 provided with a slot 18^a having the same obliquity as the guide 16. In position of assembly (Fig. 8), this guide extends into the slot 18^a, and 70 the pin 17 passes through the latter.

The adjusting bar 18 also carries a ring 18^b allowing to grip the said bar 18 and to conveniently manipulate it.

The second notch 8 is provided in a small plate 75 19 which, in position of assemblage, fits against

the front face of the adjusting bar 18 and the upper part of which is bent in order to compensate for the thickness of this bar 18 and to rest upon the support 15.

The plate 19 is provided with side lugs 19^a bent at 90° so as to embrace the edges of the adjusting bar 18 and to allow a relative longitudinal sliding movement of these two members.

Finally, the plate 19 has a notch 19^b parallel to the diagonal of the square and through which 10 the pin 12 passes.

In these conditions, if the adjusting bar 18 is vertically moved, upwardly for instance, it slides at the same time on the support 15 towards the right of the drawings, at the same time as the 15 plate 19.

The latter is then compelled, by the pin 17, to move parallel to a diagonal of the square orifice, the cross section of which diminishes.

Reversely, this cross section increases when 20 the adjusting bar 18 is moved downwardly.

The adjustment is facilitated by a scale 18^c carried by the adjusting bar 18, and the graduation corresponding to the desired adjustment is read for instance opposite the lower edge of the 25 plate 19.

When this adjustment is effected, the apparatus is locked, for instance by means of a lock nut 20 screwed on a screw-threaded extension of the pin 17.

30 This nut 20 rests on the plate 19 through the intermediary of a bearing washer 21 and of a Grover washer 22. The washer 21 constitutes moreover a socket 21^a which surrounds the nut 20 and prevents access to be had thereto otherwise than with a wrench 23 of suitable shape, thus rendering any fraudulent use impossible.

It is to be understood that, without departing from the scope of the invention, the square orifice can be replaced by an orifice having the shape of any quadrilateral, for instance a lozenge, or even 40 of a triangle of any shape.

Figs. 11 and 12 illustrate two examples.

In the first example (Fig. 11), the yarn clearing orifice, constituted by the notches 8^a and 10^a 45 of the plates 15 and 19, has the shape of a lozenge. As in the case of the square, the groove 19^b must be inclined according to the diagonal of the lozenge which passes through the apices of both notches; in this case, the large diagonal has been 50 chosen.

In the second example (Fig. 12), the yarn clearing orifice, constituted by the rectilinear edge 8^b of the plate 19 and the notch 10^b of the plate 15, has the shape of a triangle. In this case, the direction of translation of the plate 19 relatively to the plate 15 can have any direction provided it is not parallel to the rectilinear edge 8^b; the edge 8^b constantly remaining parallel to itself, the shape of the hole will always remain 60 geometrically the same.

I claim:

1. In a yarn clearer having an adjustable hole for the passage of the yarn, the combination of 65 three juxtaposed flat members two of which, adjacent the one to the other, are provided with V-shaped notches so as to form a polygonal hole for the passage of the yarn, one of the said members being fixed and the two others being movable, each one of these three members having guiding means cooperating with the two other members and intended to guide the two movable members relatively to the fixed member and the one of them relatively to the other, respectively, according to three different rectilinear directions, par- 70 75 75

allel to their plane, the guiding direction between the notched members being parallel to the diagonal passing through the apices of the notches and the two other guiding directions between the 5 three members forming a small angle between them and larger angles with the first of these three directions, and locking means for steady-
ing the said movable members relatively to the fixed member.

10 2. In a yarn clearer having an adjustable hole for the passage of the yarn, the combination of two small juxtaposed plates each having an edge cut out in the shape of a V and these edges co-operating for conjointly forming a quadrangular clearing hole, a support having guide projections, the small plate located on the side through which the yarns enters being stationary on this support; an operating plate having two parallel edges and a rectilinear groove adapted to slide on the said 15 projections of the stationary support, this groove being slightly oblique relatively to the said parallel edges, and that of the said small plates cut out in V-shape, which is located on the side through which the yarn issues being adapted to slide on the said operating plate parallel to its 20 edges and having a rectilinear groove adapted to slide on one of the projections of the stationary support, this groove being parallel to the diagonal passing through the apices of the two V-shaped 25 notches, and means for locking together the said 30

support, the two notched plates and the said operating plate.

3. In a yarn clearer having an adjustable hole for the passage of the yarn, the combination of a fixed, thin and resilient plate arranged on the side through which the yarn enters, a stationary support on which the said thin plate is secured, a movable, thick and rigid plate arranged on the side through which the yarn issues and in which a slot is provided, a small movable bar arranged 10 between the thick plate and the thin plate and in which a slot is provided, a screw-threaded spindle fixed on the thin plate and arranged for passing, without play, through the slots of the said small bar and of the thick plate, a nut screwed on this 15 spindle and arranged for clamping the said support, the small bar and the said thick and thin plates against each other, this support having a guide projection extending in the slot of the small bar, means for guiding the thick plate on this 20 small bar according to a direction slightly oblique relatively to the slot of the said bar, the latter having a hand operated control extension, both small plates each having an edge cut out in the shape of a V for conjointly forming the hole through 25 which the thread passes, and the slot of the said thick plate being parallel to the diagonal passing through the apices of both V-shaped notches.

LOUIS RÉGLEY. 30
